TIRE FOR A VEHICLE WHEEL

Brian Howard Holmes, Birmingham, and Claude Albert Hart, Sutton Coldfield, England, assignors to Dunlop Limited

Filed Nov. 28, 1973, Ser. No. 419,897

Claims priority, application Great Britain June 1, 1973

Term of patent 14 years

Int. Cl. D12—15

U.S. Cl. D12—146

FIG.1.

FIG. 2.

FIG. 3.

FIG. 1 is a perspective view of a tire for a vehicle wheel showing our new design, it being understood that the tread pattern is repeated throughout the circumference of the tire;

FIG. 2 is a plan view thereof;

FIG. 3 is a side elevational view thereof.

We claim:

The ornamental design for a tire for a vehicle wheel, as shown and described.
